J. JOHNSON.

MIXER.

APPLICATION FILED FEB. 21, 1919.

1,353,165.

Patented Sept. 21, 1920.

UNITED STATES PATENT OFFICE.

JOHN JOHNSON, OF BROOKLYN, NEW YORK

MIXER.

1,353,165.

Specification of Letters Patent. Patented Sept. 21, 1920.

Continuation of application Serial No. 102,110, filed June 7, 1916. Renewed February 21, 1919, Serial No. 278,509. This application filed February 21, 1919. Serial No. 278,467.

To all whom it may concern:

Be it known that I, JOHN JOHNSON, a citizen of the United States, residing at Brooklyn, New York, have invented certain new and useful Improvements in Mixers, of which the following is a clear, full, and exact description.

My invention relates to mixers and particularly to rotary mixers for use in mixing 10 solids, liquids or gases, with liquids, and is a continuation of my application Serial No. 102,110, filed June 7th, 1916, renewed Feb. 21, 1919, Serial No. 278,509, as to common subject-matter.

15 Rotary mixers as hitherto constructed have usually tended in operation to impart to the contents of the mixing tank a whirling motion about the axis of rotation, this whirling motion with its resulting eddying 20 effect tending to interfere with those movements of the liquid across the axis of rotation, and lengthwise thereof, which are necessary for the complete intermingling of the materials to be mixed. Moreover, in the 25 operation of rotary mixers or mixing wheels of the tangential type, the centrifugal flow of the liquid through the wheel tends also to create an eddy in the stream entering the central part of the wheel, and this eddying 30 movement of course reduces the stream to the wheel and, consequently, the mixing action of the wheel. This eddying is in part due to the fact that the material is not brought to the opening leading to the centrifugal wheel with sufficient velocity to 35 feed the wheel as fast as the wheel can deliver the material.

An object of the invention is to provide simple and efficient mixing means which 40 will obviate the difficulties heretofore experienced in mixing operations, and will insure effective intermixing of the contents of the mixing tank.

More particularly the invention aims to 45 provide improved mixing means of the rotary type which will operate to insure movement of the liquid across the axis of rotation as well as lengthwise thereof, and at the same time will check any tendency to bodily 50 whirling of the tank contents about the axis of rotation.

An important feature of the invention is the arrangement in the stream to the centrifugal wheel, of means for imposing upon 55 the stream a centripetal tendency.

Another important feature of the invention is the provision of means about the periphery of the rotary mixer or turbine wheel for converting the tangential movement of the discharged material into substantially a radial movement.

Another important feature of the invention is the provision of a member located adjacent to the centrifugal wheel and so formed as to increase the flow of material to said wheel and thereby prevent eddies in the stream above said member.

Other objects and important features of the invention will appear from the following description and claims when considered in connection with the accompanying drawings in which—

Figure 1 is a vertical elevation of the mixing device, the tank in which the mixing device is located being shown in section; 75

Fig. 2 is a plan of the mixing device proper;

Fig. 3 is a section on the line 3—3 Fig. 2; and

Fig. 4 is a section on the line 4—4 Fig. 2. 80

Referring to the drawings, 2 represents a centrifugal mixer situated at the bottom of the mixing tank 4, the mixer being driven by any suitable means such as a shaft 6 connected by gearing 8 and 10 to a power 85 shaft 12. The mixer comprises a series of turbine blades 14 supported and carried by a ring 16, the blades 14 being arranged around the central opening in the ring. These blades 14 are inclined away from the 90 direction of rotation of the wheel or mixer 2.

When the mixer is rotated rapidly, the blades 14 tend to create a centrifugal flow of the materials to be mixed, faster than 95 the materials will flow into the center opening of the mixer. This tendency would tend to create eddies in the stream above the centrifugal wheel if means were not provided to prevent this. To counteract these 100 tendencies I provide a centripetal member 16 having blades formed as shown in Figs. 1 to 3. These blades bend forwardly in the direction of rotation of the centripetal member and also bend downwardly, the 105 forward inclination increasing from the hub 18 of the member, toward the extremities of the blades. Thus formed, the member 16 tends to create a centripetal tendency in the stream, which serves to increase the 110

amount of fluid delivered to the opening of the centrifugal wheel 2.

The centripetal member 16 and the centrifugal wheel 2 may be, and preferably are, cast in one piece as shown in Fig. 3.

As the mixed materials are discharged from the periphery of the centrifugal wheel 2, they tend to travel in tangential paths across the bottom of the mixing tank 4, and then to flow up the side of the tank to a position above the wheel to replace the material drawn into the center of the wheel. The tendency of the wheel is gradually to set up a whirling motion of the entire contents of the tank in the same direction as the rotation of the wheel. This whirling motion with its accompanying eddying effect tends to counteract the mixing action of the wheel and to throw the entire tank contents, by centrifugal action, to the outer wall of the tank out of range of the operation of the wheel. In order to prevent this tendency and to insure a positive mixing of the materials and a proper direction of the mixing currents, I provide a series of stationary baffle plates 20, which are preferably so located about the periphery of the wheel 2 and at such angles to the periphery that they intersect the tangentially moving materials and tend to direct them along radial lines as shown in Fig. 2 of the drawing. These baffle plates may conveniently be formed upon segmental plates 22, which can be attached by screws 24 to the bottom of the tank, four of these baffle-carrying segment plates being shown. It will be especially noted that the baffle plates 20 are located close to and outside of the path of rotation of the blades 14 of the centrifugal wheel 2 and are curved gradually into intersecting relation to the tangents to the peripheral path of the blades 14. This particular shape of the blades 20 gives a very efficient action to the mixer which is not the case when the blades are straight, as has been heretofore suggested.

Having thus described my invention, what I claim and desire to secure by Letters Patent is:

50 1. A rotary mixer comprising a rotary body having a central opening, means for establishing a centrifugal flow of material entering said opening, and means interposed in the stream to said opening action to impose upon said stream, as it enters said opening, a centripetal tendency.

60 2. A rotary mixer comprising a rotary body having a central opening, means traveling with said rotary body for establishing a centrifugal flow of material entering said opening, and means located at spaced points about and outside the peripheral part of the path of rotation of said body and curved gradually into intersect-

ing relation to the tangents thereto, for 65 checking the tangential movement of material discharged from said rotary body.

3. A rotary mixer comprising a rotary body having a central opening, blades carried by said body outside said opening and lying transverse to but curved away from the direction of rotation of said body, other blades located along the axis of rotation with respect to said first-mentioned blades but curved in the direction of turning and 70 projecting over said central opening whereby said last-mentioned blades exert a centripetal pull upon material drawn into said opening by the centrifugal flow created by said first-mentioned blades, and said centripetal blades being feathered to pull the material along the axis toward said opening. 75

4. A rotary mixer comprising a rotary body having a central opening, blades carried by said body outside said opening and lying transverse to but curved away from the direction of rotation of said body, other blades located along the axis of rotation with respect to said first-mentioned blades but curved in the direction of turning and 80 located above and projecting over said central opening whereby said last-mentioned blades exert a centripetal pull upon material drawn into said opening by the centrifugal flow created by said first-mentioned blades. 85

5. A rotary mixer comprising a rotary body having a central receiving opening, means for establishing a centrifugal flow of the material received through said opening, and means for preventing eddies in the stream of material, said means comprising a member situated adjacent to said opening and so formed as to impart a centripetal tendency to the stream of material entering said opening. 90

6. A rotary mixer comprising a rotary body having means for establishing a centrifugal flow of material thereby creating a downward stream in the material, and means for creating a centripetal tendency in said downwardly flowing stream as it enters said rotary body. 95

7. A rotary mixer comprising a rotary body having means for establishing a centrifugal flow of material thereby creating a downward stream in the material, and means for preventing eddies in said stream, said means interposed in the downward stream of material adjacent said rotary body and acting to create a centripetal tendency in said stream. 120

Signed at Brooklyn, N. Y., this 9th day of January, 1919.

JOHN JOHNSON.
